UNITED STATES PATENT OFFICE.

HANS NATHUSIUS, OF FRIEDENSHÜTTE, KREIS BEUTHEN, GERMANY.

ELECTRIC FURNACE.

1,265,945.

Specification of Letters Patent. Patented May 14, 1918.

Application filed January 15, 1914. Serial No. 812,209.

To all whom it may concern:

Be it known that I, HANS NATHUSIUS, a citizen of the German Empire, and residing at Friedenshütte, Kreis Beuthen, Germany, have invented certain new and useful Improvements in Electric Furnaces, of which the following is a specification.

The subject-matter of my invention is an improved furnace heated by means of electric resistances, the charge being heated by radiation from the walls of the furnace, from which the air is completely shut off, either in a predetermined atmosphere or in the evacuated chamber, because heating by means of arcs by displaceable and regulatable electrodes is completely avoided.

The heating by means of resistances is effected in part by the lining of the furnace which is rammed onto the electrodes, and in part by the resistance which the charge in the furnace offers, in certain cases, to the passage of the current. It is consequently impossible for the charge to become impurified by the material of the electrodes because the charge does not contact with the electrodes themselves.

The heating by radiation is effected by the lining of the furnace heated by the resistances, particularly when the furnace is only partially filled with the charge.

The furnace is particularly intended for use in obtaining metallic zinc from zinkiferous ores on the reduction method, and is characterized by only such chemical and physical operations taking place in it as require a lower temperature than that of the electric arc. It is consequently possible entirely to obviate the employment of adjustable arc electrodes which necessitate in the masonry of the furnace, *i. e.* in the roof or in the side walls, holes which can be closed only imperfectly, and it is possible to shut off the atmospheric air completely from the interior of the furnace. The process can thus be carried into practice as desired either under the action of the atmosphere—not diluted by air or the like—of a certain gas which is supplied from the outside or is produced during the process itself, or as mentioned above in the evacuated chamber.

The improved arrangement of the electrodes and the uniform distribution of current also guarantee the interior of the furnace being heated uniformly and, if desired, in a manner readily regulatable.

The regulation of the heating is effected in this improved furnace, if desired during working, from the outside, *i. e.* at the generator or transformer by varying the voltage at the electrodes by simple switching operations or by adjusting the rotatable part of a potential regulator or by employing special auxiliary transformers formed as regulating transformers. Also, it can be effected by connecting in series with such auxiliary transformers, which will then have a constant ratio of transformation, a potential regulator or a special regulating transformer, or by connecting a regulating transformer or a potential regulator in series with the main transformer or generator which produces at the electrodes a predetermined voltage which, in turn, is varied by the apparatus connected in series. Lastly, the heating in this furnace can also be regulated by making the magnitude or phase of the added voltage directly dependent on the current sent into the electrodes.

The shape of the furnace resembles that of vertical or horizontal retorts heated heretofore by gas. The furnace preferably has the shape of a long vertical or horizontal chamber, *e. g.* of cylindrical form, which is completely lined inside with a mass, *e. g.* dolomite, which conducts electricity when hot.

One illustrative embodiment of my invention is represented by way of example in the accompanying drawing, wherein:

Figure 1 is a longitudinal section through a preferred form of my improved furnace.

Fig. 2 is a cross-section taken on the line *a—b* in Fig. 1, and

Fig. 3 is a diagram of connections.

Referring to the drawing, *A* designates the chamber of the furnace into whose walls the electrodes *E₁*, *E₂*, *E₃*, . . . are built; they terminate in electrode plates *P₁*, *P₂*, *P₃*, . . . Both the electrodes and their plates may consist of cast steel for example. They should embrace the interior of the furnace as completely as possible. The lining, through which the current flows and which is electrically heated, should be rammed about the electrodes and their plates. The electrodes are connected in such manner to the source of current that a potential difference exists between all of them, so that the electric heating current flows between the electrodes *E₁*, *E₂*, *E₃* and the electrodes *E₄*, . . .

E_5 , and E_6 and also between the electrodes E_1 , and E_4 , and E_2 and E_5 , and E_3 and E_6 , and, in certain cases also from the one electrode to the electrode of opposite sign diagonally opposite it according to the resistance 5 conditions in the furnace.

It will be readily understood that an exceedingly uniform distribution of current and consequently a like distribution of heat 10 can hereby be obtained.

In the illustrative embodiment three electrodes E_1 , E_2 , E_3 are arranged at the one side of the furnace and the three electrodes E_4 , E_5 , E_6 at the other side, each electrode 15 being electrically connected with a source of three-phase current S , as shown in Fig. 3. Obviously, instead of using three electrodes at each side only two or four or more thereof may be employed in like manner, accord- 20 ing as two-phase, three-phase or other multi-phase current is at disposal.

In the event of its being desired to distil over or condense vapors or gases the electrically heated chamber A is connected by a 25 passage or by one or more flues with one or more receivers or condensers B which, in this illustrative embodiment, does not require to be heated either electrically or otherwise. If desired, this receiver B can be 30 heated electrically in a manner analogous to that employed for the chamber A or otherwise by known means, *e. g.* by the gases from the chamber A .

The improved furnace can be advantageously employed whenever it is desired to produce in the furnace, from which the air is completely shut off, or to which certain gases are supplied to the perfectly closed chamber, a uniform temperature of a height 35 which is always below that obtainable by means of the electric arc, such as is suitable for annealing, tempering, cementation and the like of metal or iron bodies or for burning porcelain, bricks and like bodies or for 40 coking coal and obtaining by-products and in all similar cases.

I claim:—

1. A closed electric furnace having a heating or reducing chamber whose walls are 5 composed of electrically resistant material which is electrically conductive when heated, said walls having fixedly embedded therein in an air tight manner outside the chamber symmetrically disposed at opposite sides 10 of it sets of electrodes, said sets of elec-

trodes embracing the chamber; and means for supplying current to said electrodes.

2. A closed electric furnace having a heating or reducing chamber whose walls are composed of electrically resistant material 60 which is electrically conductive when heated, said walls having fixedly embedded therein in an air tight manner wholly outside the chamber and symmetrically disposed at opposite sides of it, sets of elec- 65 trodes, said sets of electrodes embracing the chamber; and means for supplying current to said electrodes in such a manner that a potential difference exists between any two and all of the electrodes substantially as 70 described.

3. A closed electric furnace having a heating or reducing chamber and a second chamber communicating with the first mentioned chamber, the walls of the heating or reducing chamber being composed of electrically 75 resistant material, which is electrically conductive when heated, said walls having fixedly embedded therein in an air tight manner entirely outside of the chamber and sym- 80 metrically disposed at opposite sides of it sets of electrodes, said sets of electrodes embrac- 85 ing the chamber; and means for supplying current to said electrodes in such a manner that a potential difference exists be- 90 tween any two and all of the electrodes sub- 95 stantially as described.

4. A closed electric furnace having a heating or reducing chamber and a second chamber communicating with the first mentioned 90 chamber, the walls of the heating or reducing chamber being composed of electrically resistant material, which is electrically conductive when heated, said walls having fixedly embedded therein in an air tight man- 95 ner entirely outside of the chamber and symmetrically disposed at opposite sides of it sets of electrodes which terminate in elec- 100 trode plates, said sets of electrodes and plates, embracing the chamber; and means for supplying current to said electrodes in such a manner that a potential difference exists between any two and all of the elec- 105 trodes substantially as described.

In testimony whereof, I affix my signature 105 in the presence of two witnesses.

HANS NATHUSIUS.
